UNITED STATES PATENT OFFICE.

HAROLD D. REICHARD, OF RACINE, WISCONSIN, ASSIGNOR TO RACINE HORSESHOE TIRE COMPANY, OF RACINE, WISCONSIN, A CORPORATION OF WISCONSIN.

DESIGN FOR A TIRE TREAD.

Application filed June 23, 1926. Serial No. 18,152. Term of patent 14 years.

To all whom it may concern:

Be it known that I, HAROLD D. REICHARD, a citizen of the United States of America, residing at Racine, county of Racine, and State of Wisconsin, have invented a new, original, and ornamental Design for Tire Tread, of which the following is a specification, reference being had to the accompanying drawing, forming a part thereof.

In the accompanying drawings:

Fig. 1 is a perspective of part of a tire embodying the design.

Fig. 2 is a cross section on the line 2—2,

Fig. 3.

Fig. 3 is a plan, on an enlarged scale, of a portion of the tire tread showing the design of Fig. 1 with the tire tread in a reversed or inverted position.

I claim:

The ornamental design for a tire tread, substantially as shown.

HAROLD D. REICHARD.
